UNITED STATES PATENT OFFICE.

WAINWRIGHT B. GERVAIS, OF CHICAGO, ILLINOIS, ASSIGNOR TO VARIETY MANUFACTURING COMPANY, OF CHICAGO, ILLINOIS, A CORPORATION OF ILLINOIS.

MEANS FOR CHECKING THE SPEED OF DOORS

1,194,991.

Specification of Letters Patent. Patented Aug. 15, 1916.

Application filed January 24, 1914. Serial No. 814,081.

To all whom it may concern:

Be it known that I, WAINWRIGHT B. GERVAIS, a citizen of the United States, and a resident of Chicago, in the county of Cook and State of Illinois, have invented a certain new and useful Improvement in Means for Checking the Speed of Doors, of which the following is a full, clear, concise, and exact description, reference being had to the accompanying drawings, forming a part of this specification.

My invention relates to doors and, more particularly, to means for checking the speed of doors, such as counterbalanced doors, etc., when such doors are being closed. It has been found in practice that doors of that type, when being closed, come together with considerable of an impact, and my invention is designed to obviate this undesirable feature.

My invention contemplates a spring or other yielding device positioned so as to engage the lower panel or section of a counterbalanced door immediately before both panels are brought together and, thus, materially decreasing the speed thereof, so that the panels will come together without causing undue noise.

My invention will be better understood by reference to the accompanying drawings, in which—

Figure 1 is an elevational view of a counterbalanced door showing the embodiment of my invention in conjunction therewith; Fig. 2 is an enlarged view of my invention showing the relative positions of the parts after the panels of the door have been brought together or closed; and Fig. 3 is a cross-sectional view taken on line 3—3 of Fig. 2.

At the outset it might be well to describe briefly one type of door to which my invention is particularly adapted and, to this end, I have shown in Fig. 1 an upper panel 4 and a lower panel 5 of a counterbalanced door, these panels being either wholly of metal or they may be of wood and metal. They are connected by means of chains 5' and 6 secured to the panel 4 at points 7 and 8, respectively, and pass over pulleys 9 and 10, suitably mounted to the framework secured to the building, the other ends of these chains being secured to rods 11 and 12 having connections at points 13 and 14 to the panel 5. The latching arrange-

ment for the door comprises a disk 15, to which is secured a handle 16, this disk being pivoted upon a suitable plate member or plate 17 secured to the section 5. The disk 15 has pivoted thereto arms 18 and 19, the outer ends of which are arranged to engage with the projections 20 and 21 secured to the framework which is mounted on the building. A spring 22 maintains the handle normally against the angle 23 and also maintains the arms 18 and 19 in their outermost positions. When the panels are brought together, the arms are snapped into place over the projections 20 and 21 and, when it is desired to open the door, the handle 16 is rotated so as to disengage the arms and thus permit the panels to be separated, or to open the door. As has before been stated, it frequently happens that when the panels are brought together, they come together with a considerable impact, thus causing a great deal of noise and also making it in some cases very dangerous for the one who is closing the door. My invention comprises a mechanism for slackening the speed of the panels as they are brought together and to this end I provide the lower panel 5 with projections 24 and 25, which may be secured to the panel in any suitable manner, and, upon the L-shaped members 26 and 27, at each side of the doorway, are provided springs 28 and 29 secured by means of bolts at their upper ends and being loose at their lower ends and engaged by bolts 30 and 31, these bolts being for the purpose of forcing the springs either out or in so as to secure the desired friction between the springs and the coöperating projections 24 and 25.

As shown in Fig. 2, the lower panel 5 is in its uppermost position, that is to say, it is in engagement with the upper panel 4 and, during the upward course of the panel 5, the projections 24 and 25 have engaged and passed over the springs 28 and 29 and, thus, the movement of both panels has been decreased so as to reduce the impact between the panels. The projections 24 and 25, as shown, are rounded so as to pass over the springs 28 and 29 quite easily, both when the lower panel 5 is raised and when it is lowered.

While I have herein shown and described one particular form of my invention, I do not wish to be limited to the precise details

shown, inasmuch as it will be apparent that other means may be employed to effect the desired result of checking the speed of a door as it is being closed. This door, it should be kept in mind, may be of any desired type.

I claim as new and desire to secure by Letters Patent:

1. A speed-checking device for vertically movable doors comprising a resilient member adapted to lie lengthwise of the side edge of the door, one end of which member is secured to the guide-way for the door and the other end of which abuts against an adjusting screw threaded into said guide-way, and a lug projecting from the side edge of the door, said lug engaging and passing over said resilient member when the door is being raised or lowered.
2. In combination a vertically movable door, an angle bar secured to the vertical edge of said door, said angle bar having one

leg projecting substantially in the plane of the door, a vertical stationary angle bar having one leg overlapping and lying substantially parallel to the leg of said first angle bar, said angle bars forming an open channel between them, a projection secured to one of said angle bars and an adjustable bowed spring secured to said other angle bar, said parts having relative movement with respect to each other so that the spring and the projection will be engaged as the door moves toward the limit of its movement in closing to check the speed of movement thereof and will be disengaged when the door reaches the closed position.

In witness whereof, I hereunto subscribe my name this 29th day of December, A. D. 1913.

WAINWRIGHT B. GERVAIS.
